Attorney

UNITED STATES PATENT OFFICE.

FRANK W. CARLSON, OF OILFIELDS, CALIFORNIA.

DEVICE FOR FASTENING BELTS.

1,391,168.

Specification of Letters Patent. Patented Sept. 20, 1921.

Application filed February 14, 1919. Serial No. 276,958.

To all whom it may concern:

Be it known that I, FRANK W. CARLSON, a citizen of the United States, residing at Oilfields, in the county of Fresno and State 5 of California, have invented certain new and useful Improvements in Devices for Fastening Belts; and I do hereby declare the following to be a full, clear, and exact description of the invention, such as will enable 10 others skilled in the art to which it appertains to make and use the same, reference being had to the accompanying drawings, and to the letters and figures of reference marked thereon, which form a part of this specification. 15

This invention relates to new and useful improvements in belt fasteners and consists of a simple and efficient device of this nature, so arranged that the ends of the belt 20 may be held securely within a holder without the necessity of perforating the belt and thereby weakening the same.

More specifically, the present invention consists in the provision of a rectangular 25 outlined holder member which is longitudinally slotted with the opposite walls tapering and having portions of the edges of the holder recessed away, and in the provision of a wedge-shaped member extending the length 30 of the slot, and having its opposite faces fluted, coöperating with the inclined walls of the holder to retain the ends of the belt.

My invention is illustrated in the accompanying drawings which, with the letters of 35 reference marked thereon, form a part of this application and in which:

Figure 1 is a side elevation showing the application of my invention.

Fig. 2 is a sectional view through the fastening device, and

Figs. 3 and 4 are views of the holder and wedge-shaped member respectively, and Fig. 5 is a detail view in side elevation of the holder.

Reference now being had to the details of 45 the drawings by letter:

A designates a holder, made of any suitable material, preferably of rectangular shape and provided with an elongated slot B, the opposite walls of which are inclined 50 relative to each other. C designates a wedge member extending the length of said slot and which member is hollow provided with transverse partitions dividing the same into cells. The outer inclined faces of said member are fluted or ribbed to effect a better frictional contact with the belt, which it is adapted to clamp against the inclined wall of the holder. Said wedge-shaped member is preferably hollow reinforced with bridges 60 C' to strengthen and brace the same and forming a plurality of sockets C, and the lower marginal edges of the holder are recessed away as at E in order to pass by an oval pulley about which the belt to which 65 the fastener is attached is adapted to pass.

What I claim to be new is:

A belt fastener comprising a rectangular frame having an interior of trapezoidal cross section and provided with a plane outer 70 face at the base of the trapezoid and longitudinally curved at the side opposite the plane face, and a wedge having fluted sides at substantially the angle of the inclined walls of the trapezoid, the wedge provided 75 with sockets in its base and the base of the wedge when inserted being substantially coplanar with the said plane faces, the interior end walls of the frame closely fitting and guiding the ends of the wedge. 80

In testimony whereof I hereunto affix my signature in presence of two witnesses.

FRANK W. CARLSON.

Witnesses:

H. B. WEST,
R. W. CAIN.
